J. H. Keeney & Co., Inc., Chicago, Ill., a corporation of Illinois

Application August 8, 1940, Serial No. 94,298

Term of patent 7 years

To all whom it may concern:

Be it known that I, Arthur C. Haggstrom, a citizen of the United States, residing at Rockford, in the county of Winnebago and State of Illinois, have invented a new, original, and ornamental Design for a Cabinet for a Loudspeaker, of which the following is a specification, reference being had to the accompanying drawing, forming part thereof.

In the drawing:

Fig. 1 is a front elevational view of a cabinet for a loudspeaker embodying my new design.

Fig. 2 is a side elevational view thereof.

Fig. 3 is a top plan view.

I claim:

The ornamental design for a cabinet for a loudspeaker, substantially as shown.

ARTHUR C. HAGGSTROM.
